UNITED STATES PATENT OFFICE.

GUSTAV BARTHEL, OF DRESDEN, GERMANY.

BUNSEN BURNER.

NO. 882,611.

Specification of Letters Patent. Patented March 24, 1908.

Application filed September 15, 1906. Serial No. 834,769.

To all whom it may concern:

Be it known that I, GUSTAV BARTHEL, a subject of the German Emperor, and residing at Dresden, Germany, have invented certain new and useful Improvements in Bunsen Burners, of which the following is a specification.

The present invention relates to a Bunsen burner for liquid fuels, for producing an extremely hot flame, resembling that of a blow-pipe or bellows. In the new burner at the periphery or at a portion thereof, of the jet of vaporized fuel entering under high pressure the mixing chamber and mingled therein with air, particles of the gas are caught up and laterally deflected without the body of the jet being affected. This deviating quantity of vapor and air is formed into a flame, which serves to keep the main jet of vapor issuing from the mixing tube in a constant state of ignition. To attain this object the mixing tube is slightly constricted by means of an internal collar, a lip, a neck or the like; or a cap is pushed over the mixing tube, having an exit which is smaller than the mouth of the tube. In front of this constriction of the mixing tube perforations are provided in the wall of the tube, through which are forced the gaseous particles which are prevented from freely leaving the mixing tube.

Around the mixing tube I prefer to locate also a chamber having perforated walls, into which there enters the gaseous mixture forced through the wall of the mixing tube. After ignition of the burner these laterally deviating quantities of vapor and air form an auxiliary flame which unites with the main flame. To aid in forming the auxiliary flame I prefer to locate the vaporizer concentrically with the mixing tube, in such manner that the auxiliary flame rushes directly through the front wall of the vaporizer at the mouth of the mixing tube.

My invention is illustrated in the accompanying drawing, in which

Figure 1 shows a Bunsen burner having a vaporizer surrounding the mixing tube. Figs. 2-4 show in section three different forms of constricted mixing tubes, which may be employed. Figs. 5-7 show like views of mixing tubes provided with a cap.

1 is the pipe feeding fuel from the reservoir below and coiled so as to present a spiral 2, the convolutions of which lie closely one against the other. From the coil 2 the pipe 3 conducts the vaporized fuel in well known

manner to the nozzle or like device 4. Opposite the latter is located the mixing tube 5, held in place by two sockets 6, 7 which may lie inside, or be pushed over, the coil 2. The front socket 7 is perforated as at 8 to admit of the flame, burning in the interior of the coil 2, which constitutes the vaporizer, passing out through it. 9 is a clamp ring which serves to separably connect the assembled parts of the burner.

The mixing tube consists of the central tube 5, perforated in any suitable manner at 10. The mouth of the tube 5 is constricted, for instance by means of an internal collar 11 (Fig. 2), a lip 12 (Fig. 3) or a neck 13 (Fig. 4) or by means of a cap 14 (Fig. 5) of any desired form, the crown of which is so shaped that the aperture is somewhat smaller than the mouth of the tube. In Fig. 5 the cap 14 has a lip 15; in Fig. 6 it has a receding eye 16 located within the tube 5. In Fig. 7 the cap 14 is so fixed on the tube 15 that between the rim of the latter and the rim of the receding eye 16, a space is left, so that a chamber is formed to receive the gaseous mixture which is prevented from flowing freely out of the tube 5. The cap 14 (Figs. 5-7) is perforated at 17, and if desired, also in the crown at 18, so that when the burner is ignited an annular flame is formed at the head of the cap also.

The perforations in the mixing tube being of greater capacity than the exit openings from the chamber surrounding said tube, the gas will issue from said exits under a pressure greater than if the perforations and exit openings were of equal capacity.

The burner operates as follows:—The fuel is fed to the vaporizer 2 in well known manner. The vapor generated rushes out at the nozzle 4 and into the mixing tube 5, drawing in air at the same time in the manner of an injector. The larger the cross-section of the mixing tube and the smaller the orifice in the nozzle 4, the larger the quantity (up to a certain limit) of air drawn into the tube 5 by the gas jet. Owing to the constriction of the tube 5, and, to the apertures in its walls, particles of the gaseous mixture are, as already mentioned, caught up at the periphery of the gas jet and conducted either laterally into a chamber, or directly into the vaporizer casing. These laterally diverted gaseous particles form, after ignition of the burner, an auxiliary flame, which serves in the first place for heating the vaporizer, and secondly, after it has left the apertures 8 in

the vaporizer casing, for continuous ignition, that is to say, for maintenance of the main flame, for which the gas jet flows out of the mixing tube with undiminished velocity.

5. The auxiliary flame is aided in keeping the main flame continually ignited, by the annular flame burning at the perforations 18 at the front of the chamber.

What I claim is:—

10. 1. In a Bunsen burner, a mixing tube provided with perforations and a constricted exit opening, causing peripheral particles of gas to deviate through said perforations, and a vaporizer surrounding said mixing tube, 15 the space between the tube and vaporizer forming a chamber to receive said diverted gases, said chamber at its exit end having openings for the issue of the diverted gas which, when ignited, forms an auxiliary 20 flame for heating the vaporizer, substantially as and for the purpose set forth.

2. In a Bunsen burner, a mixing tube provided with perforations and a constricted exit opening, causing peripheral particles of 25 gas to deviate through said perforations, and a vaporizer consisting of a pipe coiled around

the mixing tube and forming a chamber for receiving the gases thus diverted from the mixing tube, said chamber having openings at its exit end where the ignited gases form 30 an auxiliary flame for heating the vaporizer, substantially as and for the purpose set forth.

3. In a Bunsen burner a mixing tube provided with a constricted gas outlet, a vaporizer inclosing the same and two sockets closing the space between the vaporizer and the mixing tube and supporting the latter, substantially as and for the purpose set forth.

4. In a Bunsen burner, a mixing tube provided with perforations and a constricted 40 gas outlet, a vaporizer inclosing the same, sockets closing the space between the vaporizer and the mixing tube and supporting the latter, the front of which sockets is provided with a ring of perforations, all substantially 45 as and for the purpose set forth.

In testimony whereof I affix my signature in presence of two witnesses.

GUSTAV BARTHEL.
